METHOD OF AND DEVICE FOR CHARGING EXPLOSIVE PROJECTILES

Michel Précoul, Paris, France, assignor to Societe Technique de Recherches Industrielles et Mécaniques, Strim, Paris, France, a French society

Application December 17, 1954, Serial No. 476,086

4 Claims. (Cl. 86—20)

This invention relates to methods and means for 15 charging explosive projectiles.

Experience teaches that the charging of explosive projectiles, especially hollow-charge projectiles, when effected by applying the hitherto known casting methods employed for charging ordinary projectiles, occasions many disadvantages, such as irregularity in the perforating force, reduction in disruptive power, etc.

It is an essential object of this invention to provide a method of charging hollow-charge projectiles with cast explosive, whereby on the one hand the disadvantages broadly set forth hereinabove may be avoided, and, on the other hand, a maximum perforating force may be obtained notably for a hollow charge of predetermined weight and caliber.

Other features and advantages of this invention will appear as the following description proceeds with reference to the attached drawing and illustrating diagrammatically the manner in which the invention may be carried out in practice. Of course, it will be understood that the example shown in the drawing and described hereafter is solely illustrative and should not be construed as limiting the purpose of the invention, as many modifications and alterations may be made without departing from the spirit and scope of the invention.

The examples described hereafter refer to the use of a binary mixture containing 50% of hexogen and 50% of tolite.

The invention is also applicable to hexogen tolite mixtures having other proportions than 50/50, as well as to any other explosives, for example pentolite, hexogen, tolite, aluminium, etc.

The charging method of this invention is carried out by casting the product directly through the base into the body of the projectile, and its essential features are as follows:

(1) The casting is effected with a substantial feed reserve;

(2) High-temperature heating (at a temperature at least equal to the melting point of the explosive) of the charged projectile during a relatively long time period, so as to enable the heavier crystals (hexogen crystals for example), to decant or form a sedimentary layer adjacent to the front portion of the hollow charge;

(3) First clearing or pre-clearing of obstructed passage;

(4) Re-filling after the aforesaid pre-clearing; and

(5) Devices for insulating and heating the unavoidable constricted portion of the charge.

Reference will now be made to the specific example illustrated in the drawing, wherein:

Figure 1 shows in diagrammatical longitudinal section a projectile at the end of the charging operation, and

Figure 2 shows also in diagrammatical longitudinal section but on a greater scale the upper portion of the same projectile during the pre-clearing operation.

2

The projectile 1 is provided at its base end with a conventional filling funnel 2 having fitted thereon, according to this invention, an extension member 3 of a capacity substantially equivalent to, or greater than, the inner capacity of the chamber 4 in which the explosive product cast into the projectile is received.

Before effecting the charging operation each projectile is heated at about 95° C. during a time period of from 10 minutes to 60 minutes, for example, to remove any trace 10 of moisture from the inside and raise the temperature of the body, funnel and extension assembly at least to the melting point of the explosive. With this procedure any sudden cooling, contraction, etc. of the jets of cast explosive is avoided during the casting operation.

The molten explosive (for example a hexogen/tolite mixture) is stored in a constant-temperature vat, for example heated at 95° C. preferably through automatic temperature adjusting means.

The explosive product is brought to a pasty condition 20 and stirred continuously so as to keep it in a perfectly homogeneous state.

Prior to effecting the casting operation the projectile bodies are provided, as shown in Fig. 1, with a cotton or woolen sleeve 5 surrounding their throttled base portions. 25 These sleeves 5 are heated beforehand to 95° C., for example; as a substitute for cotton or woolen sleeves, ring-shaped members of light-alloy, bronze, steel or other metals may be used; in both cases the sleeves or like members are pre-heated with the aforesaid assembly. 30 The purpose of this arrangement is to retard the cooling of the explosive in the throttled region, thereby reducing any pipe formation.

Then the casting operation is carried out while constantly maintaining the explosive mixture at a relatively 35 high temperature (for example 95° C.) and stirring it to maintain its homogeneousness. The extension member 3 is filled to $\frac{2}{3}$ of its height or more so as to contain an explosive mass of a volume greater than the volume of the cavity of the projectile to be filled with explosive 40 whereby there is obtained a reserve for the feed of explosive in order to pour it into the latter.

Upon completion of the charging step, the projectile bodies are introduced into a drying oven and heated for a relatively long period, ranging for example from 10 minutes to 60 minutes, at a relatively high temperature, 45 for example 95° C. This operation has a twofold purpose:

(a) avoiding pipe formation by increasing the fluid condition of the charge during a relatively long time period, and

(b) enabling the mixture to decant or form a sedimentary layer (for example of hexogen/tolite) so that the heavier product (for example hexogen) will be deposited at the bottom, i.e. adjacent to the front portion of the hollow charge, the extra hexogen being removed from the funnel extension constituting the reserve of the heavier product.

With this method it is thus possible to "enrich" the charge proper located in the cavity of the projectile body, notably in the front portion thereof, due to the fact that the hollow-charge lining is thus surrounded directly with a more powerful, active and heavier explosive (for example hexogen) although the initial mixture (for example hexogen/tolite) is weaker and lighter, but possesses better melting and casting properties.

Consequently, the method of charging projectiles according to this invention makes it possible, from an initial less powerful but more easily handled product, to obtain 70 a more powerful, active and "concentrated" charge.

After the cooling step carried out as the projectiles are extracted from the drying oven in which the decanting step has taken place, the next step of the charging method is effected which consists in a first clearing operation or "pre-clearing."

This operation is illustrated in Fig. 2 and its purpose is to suppress systematically the cavity or pipe formations likely to occur, especially coaxially and adjacent to the top of the hollow charge. Therefore, this pre-clearing step is effected, according to this invention, in the throttled region of the base and as close as possible to the lining, over a diameter approximating the inner diameter of the base orifice. For example, the depth of penetration of the pre-clearing member may be adjusted to within a few millimeters or about $\frac{1}{10}$ of the caliber from the lining.

Upon completion of this pre-clearing step, the charging operation is terminated in accordance with the process set forth hereinabove, that is, the extension member 3 is placed again in communication with the opening for the pouring of the projectile so that the cavity created by the preliminary flow may be filled, the assembly of the extension projectile being heated for a prolonged period, for example 20 to 60 minutes, at a high temperature, 95° C., for example.

Then, the projectiles thus charged are ready for the final, conventional clearing operation designed to form the cavity for receiving the compressed or rammed priming explosive.

The hollow-charge explosives charged according to the method of this invention are characterized by a maximum penetrating power and a perfect regularity. The value of a charge thus effected is calculated more particularly as a function of the high specific gravity of the cast mixture filling the projectile cavity. Thus, in the case of a hexogen/tolite mixture 50/50 charged according to this invention the mixture specific gravity is as high as 1.67 or 1.68.

In those cases where the explosive employed does not provide the minimum specific gravity required, a method of generally improving this specific gravity is also provided by this invention, which consists in the procedure set forth hereafter.

To exemplify the method a practical embodiment thereof will be described with particular reference to a hexogen/tolite mixture.

Again, it is pointed out that other explosive mixtures and proportions may be employed without departing from the spirit and scope of the invention.

The primary mixture molten in the melting vat will consist, according to the invention, of:

(A) a quantity $2a$ of a hexogen/tolite mixture as in stock, made of 50% hexogen and 50% tolite, and

(B) a quantity a of tolite.

The resulting intermediate mixture $3a$ is extremely fluid and melts very easily.

According to this invention, a quantity a of, for example, pure hexogen in granules, crystallized or not, is added to the above intermediate mixture $3a$ after the latter has melted completely.

The resulting enriched mixture of weight $4a$ (enriched to 100% but still having a final hexogen/tolite content of 50/50) constitutes the product to be finally cast into the projectiles.

Of course, it would not constitute a departure from the principles of this invention to obtain and use a mixture having other final proportions than the 50% hexogen and 50% tolite mentioned hereinabove, as these proportions may be conditioned by the desired final results (density, perforating power, weight, casting properties, etc.). In this case the proportions $2a$, a , etc. will also vary.

The pure hexogen in granules and crystallized or not employed for the enriching step should comply with certain screening requirements, according to this invention.

By way of example it may be stated that when pure granulated hexogen is employed it should be retained to the extents of 95% in the Afnor (Association Francaise de Normalisation) Screen No. 26 which corresponds to a mesh opening of 0.315 mm. of which 75% are retained in the Afnor Screen No. 28 which corresponds to a mesh opening of 0.50 mm.

Under the same conditions, when pure crystallized hexogen is employed, up to 95% should be retained in the Afnor Screen No. 26, and of these, 65% should be retained in the Afnor Screen No. 27 which corresponds to a mesh opening of 0.40 mm.

The enriched mixture thus constituted is subsequently utilized and charged by employing the charging procedure of this invention, as set forth hereinabove.

What I claim is:

1. A method of charging by casting the cavity of a projectile body of the hollow-charge type having a liner comprising placing above the casting opening of the projectile to be charged a mass of explosive supply, said opening having the same axis as the lining axis of the hollow charge, said explosive supply comprising a molten explosive containing in suspension in the form of finely divided solid particles, a more powerful and 20 more dense explosive than said molten explosive, the volume of said mass being greater than the cavity to be filled, placing said mass in communication through said axial casting opening with the interior of said projectile, subjecting said mass and said filled projectile to a prolonged heating at a temperature at least equal to the melting temperature of the molten explosive but less than the melting temperature of the solid explosive in suspension for a period sufficient to settle the more dense explosive about the liner and then finally cooling the assembly formed by said mass and said projectile.

2. A method of charging by casting the cavity of a projectile body of the hollow-charge type having a liner comprising placing above the casting opening of the projectile to be charged a mass of molten tolite containing in suspension hexogen distributed in said mass in the form of finely divided particles, said opening having the same axis as the lining axis of the hollow-charge, the volume of said mass being greater than the cavity to be filled, placing said mass in communication with the interior of said projectile through the intermediary of said casting opening, subjecting when said charge has been completed said mass and said projectile to a prolonged heating at a temperature at least equal to the melting temperature of said tolite but less than the melting temperature of said hexogen for a period sufficient to settle the hexogen about the liner and then finally allowing the assembly formed by said mass and said projectile to cool.

3. A method of charging as set forth in claim 1 comprising after cooling separating said explosive mass superposed upon the axial casting opening from said projectile, removing the solidified explosive in the region located at the upper portion of the filled cavity of the projectile and around the axis of said cavity, replacing

60 an explosive mass above said casting opening, again placing said mass in communication with the interior of said projectile through the intermediary of said casting opening and heating said mass and said projectile for a prolonged time at a temperature at least equal to the melting temperature of said molten explosive but less than the melting temperature of the solid explosive in suspension and then finally allowing the assembly to cool.

4. A method of charging as set forth in claim 1 of a projectile of the hollow-charge type having a lining of generally conical configuration comprising after cooling removing the solidified explosive in the region located above said lining along a diameter substantially equal to that of the casting opening of the projectile and at a distance starting from the top of said lining less than 70 the caliber of the projectile, replacing the superposed

explosive mass upon the projectile above said casting opening, placing said mass in communication with the interior of the projectile through the intermediary of said casting opening, subjecting said mass and said projectile for a long time to a temperature at least equal to the melting temperature of the molten explosive but less than the melting temperature of the solid explosive in suspension and finally cooling the assembly formed by said mass and said projectile.
